UNITED STATES PATENT OFFICE.

MICHAEL PEKORA, OF PHILADELPHIA, PENNSYLVANIA.

OUTLET PLUG FOR DYE VATS.

Application filed February 27, 1923. Serial No. 621,543.

To all whom it may concern:

Be it known that I, MICHAEL PEKORA, a citizen of the United States, residing in the city and county of Philadelphia, State of Pennsylvania, have invented a new and useful Outlet Plug for Dye Vats, of which the following is a specification.

My invention consists of an outlet plug for a dye vat comprising a plug and a cap or top plate which are adapted to be connected by a screw or bolt in such manner that said screw is inclosed and thereby rendered inaccessible to the dye in the vat and to the discharging dye flowing from the vat through the outlet, while exposed heads of screws or bolts and nuts for the latter as heretofore in use for connecting the plug and cap are also dispensed with, and the cap is left intact whereby corrosion of such screws or bolts, the holes therefor and the heads and the nuts of the screws or bolts is prevented which otherwise would release the screws and allow the plug to drop from its position and be lost through the outlet which my invention is designed to obviate.

The invention is satisfactorily illustrated in the accompanying drawing, but the important instrumentalities thereof may be varied, and so it is to be understood that the invention is not limited to the specific details shown and described, as long as they are within the scope of the claims.

Figure 1 represents a side elevation of an outlet plug for dye vat embodying my invention, including also a vertical section of the adjacent outlet portion of the bottom of the vat.

Figure 2 represents a vertical section thereof on line 2—2 Figure 1.

Figure 3 represents a bottom plan view of the plug.

Similar numerals of reference indicate corresponding parts in the figures. Referring to the drawings,

1 designates the bottom or base of a dye vat, the same having therein an outlet opening on the wall of which is the cylindrical thimble 2 of metal or other suitable material, on the upper end of which is the horizontally extending flange 3 which is seated on the upper face of the bottom 1 around said opening. The lower end of said thimble is screw-threaded for the engagement therewith of the nut 4 which is adapted to be tightened on the lower face of said bot-

tom 1 around the opening therein, whereby the thimble may be firmly secured in position, the thimble forming the outlet proper for the dye from the vat, and constituting a lining of the outlet opening in the bottom 1. 60

5 designates a plug which is adapted to enter said thimble it comprising at the top the cylindrical head 6, and the tubular boss 7 cast therewith and depending therefrom, the bore of said boss being open at its upper end and closed at its lower end by the solid wall 8 of the boss.

Radiating from the exterior of said boss are the wings 9 which serve to strengthen said boss and guide the plug into said thimble. The periphery of the head 6 is conical or tapering and has a seat 10 on the upper end of the thimble 2, forming a tight joint therewith.

11 designates a cap at the top of the device, this being adapted to occupy a position above the bottom of the vat and has on its upper side the eye 12 for engagement of a suitable implement for raising said cap and consequently the plug and so opening the 80 outlet of the tank.

Depending centrally from the underside of said cap and cast or otherwise secured thereto is the screw or bolt 13 which is adapted to pass through an opening centrally in 85 the head 6 and enter the bore of the boss, the wall of said opening having thereon a screw thread which is a continuity of the thread on said boss, said threads being engaged by the thread of said screw or bolt. 90

Interposed between the head 6 and the cap 11 is the annular gasket 14 whose outer peripheral portion is adapted to rest on the flange 3 of the thimble so as to form a tight joint therewith and prevent leakage thereof 95 of the dye into the thimble and consequently into the outlet.

The gasket is formed with an opening in the centre thereof, the same being adapted to fit around an annular shoulder 15 at the 100 centre of the underside of the cap 11 for uniformly positioning said gasket. The screw 13 is connected with said shoulder and the latter is cast with or otherwise attached to said cap 11, as a reinforced-connection for 105 said screw.

It will be seen that the plug may be firmly connected with the cap or the top plate 11 by the screw 13 and the gasket 14 is accordingly held tight on the underside of the cap 110

by the forcible clamping of the head of the plug against the cap by the action of the screw 13, as hereinbefore referred to.

It will be seen also that the screw 13 is in-
5 closed in the bore of the boss 7, the dye be-
ing rendered inaccessible to the open top of
said bore by the gasket 14 nor to the bottom
thereof by the closure of said bottom due to
the solid wall 8 of the bore thereat, hence the
10 dye cannot reach the protected screw and
bore of the plug and corrode or otherwise in-
jure either of the same.

Furthermore, the cap or top plate 11 is
15 intact being without screw holes or openings
or otherwise perforated whereby the dye
cannot flow through said cap and corrode
either such holes and the bolts or screws
which if used would occupy such holes and
20 the tightening heads and nuts of such bolts
or screws exposed to the action of the dye.

In either case the plug proper is not liable
to be improperly disengaged from the cap
nor drop through the outlet and so be lost.

Having thus described my invention what
25 I claim as new and desire to secure by Let-
ters Patent, is:—

1. In combination a dye vat having a flat
bottom an outlet in the bottom thereof, a
flanged hollow thimble fitted to said opening
30 and secured therein the bottom of said

thimble being open, a plug having a central
screw-threaded socket arranged within said
thimble to close same, said socket being op-
erable through said thimble bottom, a cap
having a screw-threaded stem engaging said
35 socket and a flat gasket arranged between
said plug top and cap bottom and upon the
top of said thimble flange for preventing the
vat contents attacking said cap screw, the
weight of the vat contents serving to hold
40 said plug in position.

2. In combination a dye vat having a flat
bottom an outlet in the bottom thereof, a
flanged hollow thimble fitted to said opening
and secured therein the bottom of said
thimble being open, a plug having a disc-
45 like head and a central screw-threaded
socket depending therefrom which socket
and head are reinforced by radially extend-
ing ribs, said plug being arranged within
said thimble to close same, said socket being
50 operable through said thimble bottom, a cap
having a screw-threaded stem engaging said
socket and a flat gasket arranged between
said plug top and cap bottom and upon the
top of said thimble flange for preventing the
55 vat contents attacking said cap screw, the
weight alone of the vat contents serving to
hold said plug in position.

MICHAEL PEKORA.
